UNITED STATES PATENT OFFICE.

PAUL BURDET-CHEVALIER, OF RONSDORF, NEAR BARMEN, GERMANY.

TAPE FOR FASTENING CLOTHES.

1,095,805.

Specification of Letters Patent.

Patented May 5, 1914.

Application filed November 20, 1912. Serial No. 732,457.

To all whom it may concern:

Be it known that I, PAUL BURDET-CHEVALIER, a citizen of the German Empire, and residing at Ronsdorf, near Barmen, Germany, have invented certain new and useful Improvements in Tapes for Fastening Clothes, of which the following is a specification.

Tapes for fastening clothes are well-known, in which the fastening members, *e. g.* hooks and eyes, are connected with the tapes by weaving them in. The bases of the hooks and eyes are woven in continuous, tubular, hollow fabrics, from which the hooks and eyes project laterally and are thus securely held.

The subject-matter of the invention is a tape for fastening clothes, in which dress-fasteners are employed as the fasteners, both the upper and lower sections being inclosed in hollow fabric provided only at those parts of the tape at which the sections of the dress-fasteners are located, and which firmly secure these sections on all sides corresponding to the shape of the same.

Figure 1 of the drawings shows the fastening tape having its upper portion closed and the lower portion opened. Fig. 2 is a cross-section according to A—B and Fig. 3 is a section according to C—D in Fig. 1.

The fabric is diagrammatically represented and the parts shown having an open mesh indicate fabric of double thickness providing therebetween pockets each one of which is closed in on all sides by the surrounding fabric of single thickness. These

pockets in one strip of the fabric completely inclose the base plate *a* of one member of the fastener, the neck of the stud *b* of the fastener projecting through one face of the strip. The opposite member of the fastener is likewise seated in pockets in a second strip of the fabric, the operative part *d* of the opposite member projecting through the face of the second strip. The portions of the tape between the fasteners and around the pockets consist merely of simple woven fabric of single thickness closing in the pockets on all sides. When dress-fasteners are attached in this manner the sections are firmly connected with the tape and are immovable therein, and when the tape is of small width it can be well and readily sewn at its edges by hand and with the sewing machine to wearing apparel or the like.

I claim:

In combination with a fabric woven to provide a plurality of spaced apart portions of double thickness surrounded by portions of single thickness constituting pockets in the strip closed in on all sides, a plurality of fastener members seated in said pockets and fitting tightly therein having their operative parts projecting through the face of the strip.

In witness whereof I have hereunto set my hand in presence of two witnesses.

PAUL BURDET-CHEVALIER. [L. s.]
